DESIGN FOR A COMBINED LOCOMOTIVE AND TENDER

John W. Patton and Paul P. Cret, Philadelphia,
Pa., assignors to Edward G. Budd Manufacturing
Company, Philadelphia, Pa., a corporation
of Pennsylvania

Application November 8, 1937, Serial No. 72,704

Term of patent 14 years

To all whom it may concern:

Be it known that we, John W. Patton and Paul P. Cret, citizens of the United States, residing at Philadelphia, in the county of Philadelphia and State of Pennsylvania, have invented a new, original, and ornamental Design for a Combined Locomotive and Tender, of which the following is a specification, reference being had to the accompanying drawing, which forms a part thereof.

Fig. 1 represents in side elevation, a combined locomotive and tender embodying the design.

Fig. 2 is a perspective view thereof and on a somewhat enlarged scale.

Fig. 3 is a perspective view taken at a different angle from that shown in Fig. 2 and on a somewhat enlarged scale.

Fig. 4 is a front elevation of the design.

The dominant feature of the design is the central raised band extending from the bottom to and over a portion of the top of the front of the locomotive and the panel effect at the front along each side of said band.

We claim:

The ornamental design for a combined locomotive and tender, as shown and described.

JOHN W. PATTON.

PAUL P. CRET.
